UNITED STATES PATENT OFFICE.

WILLIAM A. SEIDLER, OF NEWARK, NEW JERSEY.

DESIGN FOR A HANDLE FOR BUTTON-HOOKS, &c.

SPECIFICATION forming part of Design No. 26,821, dated March 30, 1897.

Application filed February 19, 1897. Serial No. 624,253. Term of patent 8½ years.

To all whom it may concern:

Be it known that I, WILLIAM A. SEIDLER, a citizen of the United States, residing at Newark, in the county of Essex and State of New Jersey, have invented a certain new and useful Design for Handles for Button-Hooks or Similar Articles; and I do hereby declare the following to be a full, clear, and exact description of the invention, such as will enable others skilled in the art to which it appertains to make and use the same, reference being had to the accompanying drawing, and to letters of reference marked thereon, which forms a part of this specification.

My design has for its object to furnish a practical and at the same time ornamental external surface in handles for button-hooks or similar articles.

The leading features in my design are as follows:

In the figure is shown two centrally-located arched plain surfaces, an upper large one, corresponding in breadth to the upper part of

the handle, and a smaller lower one, corresponding to the lower narrower part of the handle, the edges of the handles having crockets formed so as to inclose the arched plain spaces in the shape of shields, two rosettes in flower-work intermediate between the two arched spaces, the lowest part of the handle tapering with plain edges and ornamented in the center with imitations of conchoids, a rosette in leaves lying between the lower shield and the conchoids, as illustrated.

What I consequently claim as a novel design as applied to the above articles is—

The design for a handle for a button-hook or similar articles, as herein described and illustrated.

In testimony that I claim the foregoing I have hereunto set my hand this 17th day of February, 1897.

WILLIAM A. SEIDLER.
